DENTAL MIRROR LIGHT

Michael N. Foster, Arlington, Tex.
(P.O. Box 1681, Fort Worth, Tex. 76101)

Filed Aug. 28, 1969, Ser. No. 18,895

Term of patent 14 years

Int. Cl. D24—03; D26—04

U.S. Cl. D24—1

Fig. 1

Fig. 2

Fig. 3

Fig. 4

Fig. 5

Fig. 6

FIG. 1 is an isometric view of a dental mirror light of the invention having a dental hand mirror shown in dotted lines in connection therewith;

FIG. 2 is a top plan view of the same;

FIG. 3 is a side elevation of the same, the opposite side being identical but reversed;

FIG. 4 is a bottom view of the light;

FIG. 5 is a front end view of the mirror showing the light and mirror holder; and,

FIG. 6 is a rear end view of the same.

The broken lines representing the dental mirror in FIG. 1 are shown for illustrative purposes only and does not form part of the claim.

I claim:

The ornamental design for a dental mirror light, substantially as shown and described.
